United States Patent

Des. 241,395
Patented Sept. 14, 1976

241,395

TABLE TOP

Ludovic Perl, 781 100th Ave., Chomedey, Laval, Quebec, Canada; Arpad Szabo, 5150 Macdonald Ave., Montreal, Quebec, Canada; and Stanley Cohen, 4th Ave., Chomedey, Laval, Quebec, Canada

Filed Dec. 26, 1974, Ser. No. 536,627

Term of patent 14 years

Int. Cl. D6—06

U.S. Cl. D6—192

fig - 2

fig - 3

fig - 4

FIG. 1 is a perspective view of a table top showing my design;

FIG. 2 is a top plan view of the table top;

FIG. 3 is a side elevation; and

FIG. 4 is an end elevation, it being noted that both longitudinal sides and both terminal sides are identical respectively.

We claim:

The ornamental design for a table top, as shown and described.
